Inventor,
William H. Reid.

UNITED STATES PATENT OFFICE.

WILLIAM H. REID, OF BROOKLYN, NEW YORK

SEPARABLE FASTENER.

1,182,857.

Specification of Letters Patent.

Patented May 9, 1916.

Application filed March 4, 1916. Serial No. 82,014.

To all whom it may concern:

Be it known that I, WILLIAM H. REID, a citizen of the United States, and a resident of Brooklyn, in the county of Kings and State of New York, have invented certain new and useful Improvements in Separable Fasteners, of which the following is a specification.

The object of the present invention is to produce a form of socket member in the fastener device of the type known as resilient head and socket, wherein the operation of piercing the head of the socket member adjacent the base is obviated by reason of a special form of a tongue member, that is formed by merely providing a special configuration of the edges of the blank, and which tongue is given the special bending operation.

A further object of the invention is to provide such a construction in which the socket member will be integral with the tongue, so that the device comprises simply two members, the spring member and the body member.

In the accompanying drawing showing one embodiment of my invention, Figure 1 is a plan view of the device. Fig. 2 is a vertical section on the line 2—2 of Fig. 1. Fig. 3 is a vertical section on the line 3—3 of Fig. 1. Fig. 4 shows a head member that cooperates with the socket member of Fig. 1. Fig. 5 is a plan view of the spring member. Fig. 6 shows the blank as cut out. Fig. 7 is an edge view of the blank. Fig. 8 shows the blank with the head portion of the tongue pressed into final shape. Fig. 9 is a side elevation of the blank as shown in Fig. 8. Fig. 10 shows a blank of Fig. 9 with the tongue bent over on to the base; and Fig. 11 is a section through the form of button as at present in use.

Heretofore fasteners of this character have been provided in which the base 12 has a head 13 formed integral therewith by a simple die operation of expanding the center of the blank to form a substantially semi-spherical head or cap, as shown in Fig. 11. This cap has been provided with openings or slots 14 and 15 on two opposite sides, adapted to receive a spring similar to the spring 16 shown in Fig. 5. This spring had its end portions 17 and 18 projecting into the slots 14 and 15, to engage the head on the head member, such as the head 19 on the member 20, as shown in Fig.

4. But it has been found very difficult in practice to produce the openings 14 and 15 in the members, by reason of their being of a very small size. To overcome the necessity of cutting or punching such slots, I provide a button which has a base member 21, and a cap member 22 in the form of a band having an enlargement at its middle portion. This band is preferably made integral with the base member, as shown, and is provided in the blank with a circular enlargement 23 connected by a strip 24 with the base 21, and having a strip 25 at the free end. The disk portion 23 is engaged by proper dies 60 to give it a cap shape 26, preferably semi-spherical and this cap has upright portions 27 and 28, that extend vertically downward from the cap, and are formed by bending upward the portions of the strips 24 and 25 70 adjacent the cap, as indicated in Fig. 9. By this means it will be seen that the cap will have its opposite sides between the upright portions 27 and 28 free, and which are off-set from the plane of the strip portions 24 and 25. The cap member is next bent over on top of the base 21 that is provided with a central bore 29, and strip 24 is bent at its connection with the base 21, so that the cap will now be brought opposite the opening 29, as indicated in Fig. 8.

The spring member 16 as shown in Fig. 5 is applied to the base with the spring portions 17 and 18 lying adjacent the side edges of the upright portions 27 and 28, and the portions 24 and 25 of the band will engage the base between the spring ends. This form of a member usually is the side edges bent over or beaded as at 30, to engage the outer portion of the spring 16 and hold it 85 in position. The strip portion 24 is preferably bent over on top of this spring, as indicated in Figs. 2 and 10. The extremity of the cap member or strip 25, will also be engaged by the bead 30 that will serve to 100 retain the cap member in position on the base 21. It will thus be seen the spring portions 17 and 18 will lie beneath the portions of the cap member, that will overhang them and prevent their being forced 105 upward by the head 19. These spring members will project across opposite portions of the bore 29, as indicated in Fig. 1, and when the head enters the socket, the spring members will grip the head and retain the two 110 members together in locked position. It will be further seen that the spring mem-

bers engage the side edges of the upright portions 27 and 28, that limit the inward movement of the spring members, as clearly shown in Figs. 1 and 4.

5 It will thus be seen that I have provided a construction in which there is a head member having undercut portions on two opposite sides to receive the spring members and hold them properly shaped to engage the 10 head member; and that the spring members are prevented from being forced upward by the head, because of the over-hanging of the cap members. But such construction is provided without any openings being 15 formed in the cap member at any stage in the manufacture, and is a result of the configuration of the margins of the blank and of very simple bending operations.

Having thus described my invention, 20 what I claim is:—

1. A resilient socket member for a head and socket fastener, comprising a base member having a central bore to admit the head, a member extending across the base and having two upright portions adjacent the bore margins connected at the top by a dome-shaped portion whose opposite sides project over said bore margins between said upright portions, and a wire spring on the 30 base having portions extending across the margins of the said bore in the base adapted to engage the head, which said spring portions lie beneath the said dome portions and engage the said upright portions.

35 2. A resilient socket member for a head and socket fastener, comprising a base member having a central bore to admit the head, a member extending across the base and having two upright portions adjacent the bore connected at the top by a dome-shaped portion whose opposite sides project over said bore margins between said upright portions, and a wire spring on the base having portions extending across the margins of 40 the said bore in the base adapted to engage the head, which said spring portions lie beneath the said dome portions and engage the said upright portions, the said base member having its margins beaded to inclose 45 a part of the spring member and to secure the said dome member at its ends to the base.

3. A resilient socket member for a head and socket fastener, comprising a base member having a central bore to admit the head, 55 an integral extension of the base member bent over to lie against the base and having two upright portions adjacent the bore margins connected at the top by a dome-shaped portion whose opposite sides overhang the bore margins between said upright portion, and a wire spring on the base having portions extending across the margins of the said bore in the base adapted to engage the head when inserted, which said spring portions lie beneath the said dome portion and engage the said upright portions of the said extension.

4. A resilient socket member for a head and socket fastener, comprising a base member having a central bore to admit the head, 70 an integral extension of the base member bent over the base and having two upright portions adjacent the bore margins connected at the top by a dome portion whose opposite sides overhang the bore margins between said upright portions, and a wire spring on the base having portions extending across the margins of the said bore in the base adapted to engage the head when 75 inserted, which said spring portions lie beneath the said dome portion and engage the said upright portions of the said extension, the said base member having its margins beaded to inclose a part of the spring member and to secure the said extension at its 80 ends to the base.

5. A resilient socket member for a head and socket fastener, comprising a base member having a central bore to admit the head, 90 a non-apertured cap member extending across the base and provided with a dome shaped portion whose opposite side edges overhang the bore margins, and a wire spring on the base having portions extending across the margins of the said bore in the base adapted to engage the head member when inserted, which said spring portions lie beneath the said cap projections, and which normally engage the margins of 95 said cap member to hold the spring in said head-engaging position.

WILLIAM H. REID.
